UNITED STATES PATENT OFFICE.

WILLIAM D. GHARKY, OF PHILADELPHIA, PENNSYLVANIA.

DESIGN FOR A TELEPHONE-POLE BOX.

SPECIFICATION forming part of Design No. 33,594, dated November 20, 1900.

Application filed September 7, 1900. Serial No. 29,322. Term of patent 14 years.

To all whom it may concern:

Be it known that I, WILLIAM D. GHARKY, a citizen of the United States, residing at Philadelphia, in the State of Pennsylvania, have invented and produced a new and original Design for a Telephone-Pole Box, of which the following is a specification, reference being had to the accompanying drawings, forming part thereof.

Figure 1 is a plan sectional view of a telephone-pole box, showing my new design. Fig. 2 is a perspective side view of the same.

As shown in the drawings, the leading or material feature of my design consists of the configuration of the body part of the box A, having an open front *a*. The back B is formed with a central depression *b'*, extending vertically the length of the box, and curved convex portions *b*, which merge into the sides S, and form, with the depressed por-

tion, undulations extending across the back. The top T has an upward curve or slant that gives a balanced effect to the body of the box.

As a whole the box presents a very graceful and pleasing appearance, besides being well adapted to the purpose for which it is designed, the most material feature being the form of the back B.

Having described my invention, what I claim as new, and desire to secure by Letters Patent, is—

The design for a telephone-pole box, as herein shown and described.

In testimony whereof I have signed my name to this specification in the presence of two subscribing witnesses.

WM. D. GHARKY.
